UNITED STATES PATENT OFFICE

2,627,954

FLUID TRANSMISSION

Warren E. Lewis, Bradley, Ill.

Application November 15, 1948, Serial No. 60,098

3 Claims. (Cl. 192—3.2)

1

The present invention relates to new and useful improvements in fluid transmissions for engines to provide a variable speed ratio between the motor and drive shaft and is designed particularly for use with motor driven vehicles.

An important object of the invention is to provide a fluid transmission including a drive rotor and a driven rotor having a novel interfitting vane construction.

A further object is to provide a fluid drive including drive and driven rotors having vanes movable relative to each other in fluid driving relation and also constructing the vanes for frictional engagement to provide a positive drive between the drive and driven rotors.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a longitudinal sectional view of the complete fluid transmission unit;

Figure 2 is a transverse sectional view taken on a line 2—2 of Figure 1;

Figure 3 is a fragmentary view in elevation of the drive rotor;

Figure 4 is a similar view of the driven rotor;

Figure 5 is a fragmentary transverse sectional view taken on a line 5—5 of Figure 1 and showing the vacuum control unit for the fluid transmission and;

Figure 6 is a sectional view taken on a line 6—6 of Figure 5.

Referring now to the drawings in detail wherein for the purpose of illustration I have disclosed a preferred embodiment of the invention the numeral 5 designates the crank or power operated shaft of an engine for a drive rotor designated generally at 6 and which comprises a disc 7 cast or otherwise suitably secured to shaft 5 and having an annular outer wall 8 formed with an inwardly projecting flange 9.

A plurality of concentrically arranged groups of vanes or impellers 10 are suitably carried by disc 7 and project from the inner surface of the disc to provide an outer circularly arranged group of vanes or impellers 11 positioned behind the flange 9, an intermediate circularly arranged group of

2

vanes or impellers 12 and an inner circularly arranged group of vanes or impellers 13.

The groups or concentric rows of vanes or impellers 11, 12 and 13 are spaced radially with respect to each other and the longitudinal edges of the intermediate vanes or impellers 12 taper as shown at 14 and the outer edge of the inner vanes or impellers 13 taper as shown at 15.

Reinforcing spacing plates 16 are suitably secured between adjacent vanes or impellers 12 and similar reinforcing spacing plates 17 are suitably secured between adjacent vanes or impellers 13. The spacing plates 16 and 17 rigidly connect the outer or free ends of the respective groups of vanes or impellers to each other.

The outer, intermediate and inner groups of vanes or impellers 11, 12 and 13 are inclined with respect to each other from a radial position as shown more clearly in Figure 2 of the drawings.

A driven rotor is designated generally at 18 and comprises a disc 19 having its edge positioned adjacent flange 9 and provided at its inner surface with outer and inner concentrically arranged groups of vanes 20 and 21 which project between the vanes or impellers 11, 12 and 13 of the drive rotor 6. The longitudinal edge of vanes 20 and 21 are parallel to the adjacent edges of the vanes or impellers 11, 12 and 13 and taper to correspond therewith. The outer ends of vanes 20 and 21 are also reinforced by spacing plates 22 and 23 respectively, and are also inclined from a radial position as shown in Figure 2 of the drawings.

The outer surface of disc 19 of the driven rotor is formed with a channeled hub 24 which is slidably connected to a driven shaft 26 by means of splines 27. The front end of shaft 26 is formed with a socket 28 in which the rear end of shaft 5 is journaled.

The driven rotor 18 is moved toward and away from drive rotor 6 by means of a yoke 29 engaged in a channel of collar 24 and connected to a shaft 30 operated by a vacuum control unit 31 of a conventional type and including a vacuum line 32 attached to the intake manifold or carburetor of an engine to provide a variable torque control for the transmission.

The rotors 6 and 18 are enclosed in a sectional housing 33 provided with liquid-tight bearings 34 and 35 for the shafts 5 and 26 respectively, the housing 33 containing a suitable quantity of oil or other liquid.

The vacuum control unit 31 is connected to a clutch pedal 36 or to a conventional automatic control (not shown) and to thus actuate the driven rotor 18 in a movement toward or away

from drive rotor 6. The vanes 20 and 21 are thus moved longitudinally between vanes 11, 12 and 13 to thus vary the rotation of driven rotor 18 by the constant drive rotor 6. Movement of the tapered vanes 20 and 21 into tight friction gripping engagement with vanes 11, 12 and 13 will provide a positive drive connection between shafts 5 and 26.

The vacuum controlled unit varies the driving ratio between rotors 6 and 18 in accordance with the variations in the load, an acceleration of the motor decreasing the vacuum in vacuum control unit 31 and allows the motor to increase its speed proportionately, thus giving an automatic variable speed and power control.

The driven rotor 18 is retracted rearwardly to the limit of its travel into a neutral position and will enable the manual operation of a suitable reverse gear mechanism which may be positioned back of the fluid transmission unit.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A fluid transmission comprising a casing for containing a liquid, a one-piece power shaft and a driven shaft journaled in opposite sides of the casing, a hollow rotor fixed to the power shaft and having an open side, a second rotor slidably keyed to the driven shaft at the open side of the first named rotor, and vanes projecting from the opposing sides of the rotors, said vanes being of elongated flat tapering construction disposed parallel to the axis of the shaft and arranged in concentric rows with the rows of vanes of one rotor work-

ing between the rows of vanes of the other rotor into and out of edgewise frictional engagement with each other.

2. A fluid transmission comprising a casing for containing a liquid, a one-piece power shaft and a driven shaft journaled in opposite sides of the casing, a hollow rotor fixed to the power shaft and having an open side, a second rotor slidably keyed to the driven shaft at the open side of the first named rotor, flat elongated vanes disposed parallel to the axis of the shafts and fixed at one end to the opposing sides of the rotors and tapering toward their free ends, said vanes being arranged in concentric rows with the rows of vanes of one rotor working between the rows of vanes of the other rotor, and spacing plates between adjacent vanes adjacent their narrow ends to rigidly support the vanes of one rotor in edgewise frictional engagement with the vanes of the other rotor.

3. The combination of claim 1 wherein said vanes of adjacent concentric rows are inclined edgewise with respect to each other.

WARREN E. LEWIS.
